UNITED STATES PATENT OFFICE.

WILLIAM ARMSTRONG WOODESON, OF GATESHEAD, ENGLAND.

STEAM-ACTUATED VALVE.

SPECIFICATION forming part of Letters Patent No. 655,537, dated August 7, 1900.

Application filed December 7, 1899. Serial No. 739,466. (No model.)

To all whom it may concern:

Be it known that I, WILLIAM ARMSTRONG WOODESON, a subject of the Queen of Great Britain and Ireland, residing at Gateshead, in the county of Durham, England, have invented Improvements in Steam - Actuated Valves, of which the following is a specification.

This invention relates to means for distributing actuating fluid in engines or motors—*e. g.*, those of direct-acting steam-pumps—of the kind in which the slide-valve that controls the admission and the exhaust of the motor-cylinder is moved, so as suddenly to open and close the admission and exhaust ports to their full extent, its actuation being effected by the live steam itself under the control of an auxiliary slide-valve operated by a suitable moving part, as the cross-head of the piston-rod. The invention has for its object to simplify, and consequently cheapen, the construction of apparatus of this kind.

The accompanying drawings represent, by way of example, the motor of a direct-acting steam-pump provided with steam-distributing apparatus according to this invention.

Figures 1 and 2 show the motor-cylinder and the valve-chest as seen from opposite sides of a vertical central sectional plane. Figs. 3, 4, and 5 show the same in section on the lines III, IV, and V, respectively, of Figs. 1, 2, 6, and 8 as seen from above. Figs. 6 and 7 show the liner respectively in vertical central section and in plan; and Fig. 8 is a development 35 of the periphery of the liner, the plane of division being indicated at VIII in Fig. 7.

According to this invention the main slide-valve 1 and the auxiliary slide-valve 2 are accommodated in a single liner 3, which is of suitable material, as cast-iron, and is provided with a transverse partition 4 to form two chambers 5 and 6 for the valves 1 and 2, respectively. The main valve 1 is of the piston type, being provided with four rings 7, 8, 9, and 10, (integral or not with the body of the valve,) that fit the liner 3, and between which there are three portions of smaller diameter that form chambers 11, 12, and 13, of which, when the piston 14 of the motor is in its highest position, (shown in Figs. 1 and 2,) the highest chamber 11 forms a communication between a port 15, which is in the

liner 3 and is connected by a passage 16 (in the liner or in the valve-chest 17, or partly in each, as shown) with the steam-inlet 18 of the valve-chest and a port 19 in the liner 3, connected by a passage 20 with the upper end of the cylinder 21, while the middle chamber 12 forms a communication between an exhaust-port 22, which is in the liner and is in permanent connection with the exhaust-passage 23 of the valve-chest, and a port 24, connected by a passage 25 with the lower end of the cylinder 21. The ports and passages in the liner are most clearly shown in Figs. 6 and 8. At the same time the upper and lower ends of the cylinder are prevented from communicating with the exhaust-passage 23 and the steam-inlet 18, respectively, by the rings 8 and 9 of the valve 1. When, on the contrary, the piston 14 is at the lower end of the cylinder 21, the valve 1 is in such a position that the upper end of the cylinder is in full communication with the exhaust-passage 23 through the passage 26 and the ports 27 and 22, while the lower end of the cylinder is in full communication with the steam-inlet 18 through a passage 28 and two ports 29 and 30, of which the latter, 30, is in permanent connection with the steam-inlet 18 through the passage 16. In order to balance the main valve 1, passages 31 32 33 34 (forming almost complete rings) are formed in the wall of the liner as continuations of the ports 19, 27, 24, and 29, respectively, so as to surround the rings 8 and 9 of the valve 1 when these rings are opposite to the corresponding ports. The auxiliary valve 2 is also of the piston type and is provided with two rings 35 and 35^a, between which a portion of smaller diameter forms a chamber 35^b, which is in permanent communication through a port 35^c and a passage 16^a, both in the liner, with the passage 16 and which when the main valve 1 is in the position shown is in communication with the upper end of the interior of the liner through a port 36, a passage 37, and a port 38, all in the liner, and the steam thus admitted thereto keeps the main valve 1 in the position shown, steam from the lower end of the chamber 5 of the liner having during the downward movement of the valve 1 been expelled to the exhaust-passage 23 through a port 39, a passage 40, and a port 41, all in the

liner, the upper end (above the valve 2) of the chamber 6, a port 42 and a passage 43, both in the liner, and the port 22. When the valve 1 is at the upper end of its stroke, it is kept in position by steam reaching the lower end of its chamber 5 from the chamber 35^b of the valve 2 through a port 44, a passage 45, and a port 46, all in the liner, steam from the upper end of the chamber 5 of the valve 1 having during the upstroke of the valve 1 been expelled to the exhaust-passage 23 through a port 47, a passage 48, a port 49, the lower end of the chamber 6, a port 50, and a passage 51, leading to the passage 43, all these ports and passages being in the wall of the liner. The positions of the ports 39 and 47 in the chamber 5 are such as to cause the main valve 1 to be cushioned at the ends of its strokes. The operation of the auxiliary valve 2 is effected by the cross-head of the pump-rod 53, which strikes at the ends of its up and down strokes, respectively, against tappets 54 and 55, fixed on a rod 56, which is connected by a lever 57, pivoted at 58 to a bracket 59, secured to one of the covers 60 of the valve-chest 17. When the valve 2 is moved by the cross-head from one to the other of its extreme positions, it immediately causes live steam to pass from its chamber 35^b to the proper end of the chamber 5 and places the other end of that chamber into communication with the exhaust-passage 23, so as to effect a sudden movement of the main valve, such as to put the two ends of the motor-cylinder quickly into full communication with the steam-inlet 18 and the exhaust-passage 23, respectively. Through the other cover 61 of the valve-chest 17 projects a spindle 62, which is fixed to the main valve 1 and is provided with a handle 63. This device has the twofold object of indicating the movements of the main valve when the pump is in operation and of enabling the main valve to be worked up and down by hand for awhile when the pump has been stopped for some time, so as to make sure of the freedom of the valve in its chamber and to get rid of any slight impediment that there may be.

It will be obvious that although the invention has been described in its application to an engine or motor whose piston has an up-and-down movement the direction of motion of the piston in relation to the vertical is immaterial to the application of the invention.

What I claim, and desire to secure by Letters Patent, is—

1. Means for distributing and controlling the actuating fluid in engines or motors comprising a main valve and an auxiliary valve placed in line with each other and working within a liner having ports through its walls and passages formed in its outer walls connecting the ports with the steam-inlet, exhaust-outlet and with the motor-cylinder, as set forth.

2. Means for distributing and controlling the actuating fluid in engines or motors com-

prising a main valve and an auxiliary valve placed in line with each other and working within a liner divided into two chambers by a partition-plate, as set forth.

3. Means for distributing and controlling the actuating fluid in engines or motors comprising a main valve and an auxiliary valve placed in line with each other and working in two valve-chambers contained within the same liner having ports through its walls and passages formed in its outer walls connecting the ports with the steam-inlet, exhaust-outlet and with the motor-cylinder and the two valve-chambers together substantially as described.

4. Means for distributing and controlling the actuating fluid in engines or motors comprising a main valve and an auxiliary valve placed in line with each other and working in a liner divided into two valve-chambers by a partition-plate and ports and passages formed in the wall of the liner connecting the steam inlet and exhaust passages with the motor-cylinder and the two valve-chambers substantially as described.

5. Means for distributing and controlling the actuating fluid in engines or motors comprising two valve-chambers in line with each other and contained within the same liner, a main distributing-valve in one of said chambers, an auxiliary distributing-valve in the other of said chambers, and adapted to operate the said main distributing-valve by controlling the passage of actuating fluid thereto, and means for moving said auxiliary slide-valve to and fro, as set forth.

6. Means for distributing and controlling the actuating fluid in engines or motors comprising a main valve and an auxiliary valve placed in line with each other, and working in two valve-chambers contained within the same liner, ports and passages formed in the wall of the liner connecting the steam inlet and exhaust passages with the motor-cylinder and the two valve-chambers, and means for operating said auxiliary valve to and fro to control said ports and passages, substantially as described.

7. Means for distributing and controlling the actuating fluid in engines or motors comprising two valve-chambers in line with each other and contained within the same liner, ports and passages formed in the wall of the liner connecting the steam inlet and exhaust passages with the motor-cylinder, and the two valve-chambers together, an exhaust-port near each end of the main distributing valve-chamber and adapted to cause the valve to be cushioned at the end of its strokes as set forth.

8. Means for controlling the passage of actuating fluid to or from an engine or motor cylinder 21 comprising two valve-chambers 5, 6 in line with each other and contained within the same liner 3 a main slide-valve 1, an auxiliary slide-valve 2, an inlet 18 for actuating fluid, an exhaust-outlet 23, passages

formed in the wall of the liner 3 and adapted to put the ends of said cylinder 21 into full communication respectively with the said inlet 18 and with the said exhaust-outlet 23 through the chamber 5 containing the said main valve when the said valve is in one of its end positions, means for moving the said auxiliary valve 2 to and fro, and passages formed in the wall of the liner for connecting the chamber 6 with the inlet 18, the exhaust-outlet 23, and the chamber 5, so as to put the

ends of the chamber 5 into communication respectively with the inlet 18, and the exhaust-outlet 23 for the purpose of moving the said main slide-valve 1 quickly from one of its extreme positions to the other.

Signed at Gateshead, England, this 15th day of November, 1899.

WILLIAM ARMSTRONG WOODESON.
